UNITED STATES PATENT OFFICE

2,437,778

PORTABLE SUPPORT FOR INVALIDS

Butler Ames, Boston, Mass., assignor to The Walkabout Company, Lowell, Mass., a corporation of Massachusetts

Application February 2, 1944, Serial No. 520,745

9 Claims. (Cl. 155—22)

1

This invention pertains to portable supports for individuals, for example persons incapacitated from walking by reason of infirmity or age, or those liable to be subjected to extreme weariness from prolonged standing or walking, and relates more particularly to an improved support of the general type disclosed in United States patent to Ames 2,282,689 dated May 19, 1942.

The support of the present invention, like that disclosed in the patent, comprises two substantially rigid supporting units normally disposed in spaced substantially parallel relation and between which the user stands or sits, and a back to which both supporting units are hinged. The frames of the supporting units and back are in general similar to the corresponding parts of the patented device, being made of thin and light but very stiff and rigid tubing. The top or hand supporting bar or rail of each supporting unit is preferably integrally continuous with the front and rear legs of the respective unit, while the lower, stretcher bar of each supporting unit is welded to the legs, and the constituent bars of the back are welded together. The hinge connections between the supporting units are likewise in general similar in structure and function to the corresponding portions of the patented device, being so designed as to permit the supporting units to be swung through arcs of approximately 180° and placed in parallel folded positions for convenience in shipping or storing the support.

As disclosed in the aforesaid patent, the support is provided with wheels at its forward end only and normally rests upon skids at its rear end. These skids are effective in preventing the device from getting out of control of the user, for instance when on an incline, but on the other hand make it necessary to expend more energy than may sometimes be desirable in propelling the device.

Objects of the present invention are to provide an improved support of the type disclosed in said patent but which is easy to propel, which is light in weight and foldable for transportation; to provide a four-wheeled support having swiveled front wheels thereby to facilitate steering it; to provide a four-wheeled support which is safe for the user even on an incline; to provide a wheeled support having brakes which are readily controlled by the user even though the user be weak or infirm; to provide a wheeled support which may safely be left standing alone without danger that it will run away; to provide a support which is firm and stable; to provide a support having provision for the optional employment of crutch

2

devices to assist in supporting the user; to provide wheel-supported crutches which are independently adjustable as to height and relatively movable toward and from each other to accommodate users of different sizes and to yield to bodily movements; and to provide a wheeled support having swiveled front wheels but so designed that the front wheels do not drag when the device is folded for transportation.

10 Other and further objects and advantages of the invention will be pointed out in the following more detailed description and by reference to the accompanying drawings wherein

Fig. 1 is a side elevation of the improved support set up and ready for use, but omitting the crutches;

Fig. 2 is a rear elevation of the device shown in Fig. 1;

Fig. 3 is a side elevation of the device of Fig. 1 as it appears when folded for storage or transportation, the seat being omitted;

Fig. 4 is a front elevation of the device showing the crutches in operative position, the seat being broken away;

25 Fig. 5 is a fragmentary, diametrical section to larger scale, showing details of the hinge means which connects the back with each supporting unit;

Fig. 6 is a fragmentary diametrical section, to larger scale than Fig. 1, through one of the rear legs illustrating details of the rear wheel brake;

Fig. 7 is a fragmentary diametrical section, to larger scale than Fig. 6, showing further details of the brake;

35 Fig. 8 is a view generally similar to Fig. 6 but illustrating details of the front wheel brake;

Fig. 9 is a longitudinal section through the hand-supporting rail of one of the units, illustrating details of the brake controller;

40 Fig. 10 is a side elevation of a tubular guide member constituting a portion of the hand supporting rail;

Fig. 11 is a side elevation of a cam sleeve forming a part of the brake controller;

45 Fig. 12 is a transverse section, to larger scale, substantially on the line 12—12 of Fig. 9;

Fig. 12a is a fragmentary plan view of the forward end portion of the hand grip of the brake controller showing the retaining latch;

50 Fig. 13 is a fragmentary section on the line 13—13 of Fig. 12a;

Fig. 14 is a section on the line 14—14 of Fig. 13;

Fig. 15 is a side elevation of the upper part of the crutch staff showing the arm-pit pad;

55 Fig. 16 is a fragmentary elevation, partly in

diametrical section, of the upper part of the crutch staff socket and the lower part of the restraining bracket;

Fig. 17 is a fragmentary plan view of the crutch-restraining bracket;

Fig. 18 is a fragmentary side elevation of the stretcher bar of one of the units showing the lower end of the crutch socket attached thereto; and

Fig. 19 is a plan view of a connecting pin having a retaining ring associated with it.

Referring to Fig. 2 of the drawings, the numeral 1 designates the back of the support. This back comprises parallel, substantially horizontal stretcher bars 2 and 3 which are rigidly united at their opposite ends, for example by brazing or welding, to a pair of hinge sleeves 4 and 5 forming a part of the hinge means which connects the back to the respective supporting units. The supporting units are alike and each comprises a rear leg 6 (Figs. 1 and 3), a front leg 7 and an upper or hand-supporting rail comprising the aligned members 8 and 8^a, united by a tubular guide member 8^x (Fig. 10) hereinafter more fully described. Each supporting unit also comprises a stretcher bar 9 spaced a substantial distance below the hand-supporting rail and substantially parallel to the latter, the opposite ends of the stretcher bar being rigidly united to the rear and front legs 6 and 7 by welding, brazing or the like. The parts 6, 7, 8, 8^a and 9, as well as the top and bottom rails 2 and 3 of the back, are preferably formed of thin but very rigid and strong metal tubing, for example drawn stainless steel tubing. As here illustrated the rear leg 6 is integrally joined with the part 8 by a smoothly bent portion 10 of the tubular material, while the front leg 7 is integrally united to the part 8^a of the hand-supporting rail by the smooth bend 11.

The front and rear legs 6 and 7 of the unit diverge downwardly away from each other, the upper portions of these legs preferably making an angle of approximately 5 1/4° with the vertical. Likewise the hinge members 4 and 5 of the back diverge downwardly from each other making a similar angle of 5 1/4° with the vertical so that the axes of these hinge sleeves 4 and 5 make angles of approximately 84 3/4° with the connecting rails 2 and 3. The downward divergence of the hinge sleeves 4 and 5 provides for stability of the device by spreading the supporting units apart at their lower portions, while the inclination of the legs of the unit causes the front wheels of the two units to be elevated from the floor when the device is folded as shown in Fig. 3 so that only two of the wheels, that is to say the rear wheels of the device, then contact the floor. This prevents the freely swiveling front wheels from interfering with the transportation of the folded device when wheeling it along on its rear wheels in the position of Fig. 3.

As illustrated in Fig. 5, the rear leg 6 of each unit extends down through a corresponding hinge sleeve 5 of the back member located above the stretcher bar 9 of each unit. Each leg 6 is provided with a fixed collar or annulus 15 welded to the leg and having its upper edge shaped to provide teeth 16 of truncated triangular shape. The lower end of the hinge sleeve 5 is wedged to increase its diameter as shown in Fig. 17 and within this enlargement there is fixed, as by brazing, a ring or annulus 18 whose lower edge is shaped to provide teeth 19, also of truncated triangular shape and designed to fit normally within

the space between the teeth 16 thus to prevent relative rotation of the leg 6 and the sleeve 5. Just above the upper end of the sleeve 5, the leg 6 is provided with an externally screw threaded flange 20 with which engages a peripherally knurled nut 21 having its lower end normally in engagement with the upper end of the sleeve 5 so as to prevent relative axial movement of the sleeve 5 and the leg 6. However, by retracting the nuts 21, the entire back of the device may be raised sufficiently to disengage the teeth 16 and 19, whereupon the supporting units may be swung about the axes of the legs 6 so as to dispose the supporting units in substantially parallel planes with the back interposed between them as shown in Fig. 3. The front and rear legs of the device are so bent that their lower portions 6^a and 7^a (Figs. 1 and 2) are substantially vertical.

The lower end of each rear leg 6 (Fig. 6) is provided with a fixed collar 22 brazed or otherwise rigidly secured to the leg, such collar constituting the upper part of a forked bracket 23 (Fig. 2) having bearings for the rear wheel 24. This rear wheel may be of conventional wire-spoke construction, having a rubber or other resilient tire 24. As above noted, the collars 22 are rigidly secured to the lower ends of the legs 6 and the brackets 23 are so arranged that the planes of the rear wheels are always parallel.

Referring to Fig. 6, the lower portion 6^a of the leg is shown as provided with an internal elongate bushing 25 having a radial flange 25^a at its lower end which underlies the collar 22 and this bushing 25 is shaped to provide an elongate chamber 26 which houses a long coiled spring 27 whose upper end bears against the upper wall of the chamber 26 and whose lower end bears against the upper surface of a brake shoe 30 designed to cooperate with the tire of the rear wheel. A sleeve 28, arranged within the bushing 25, constitutes an inner wall for the spring chamber 26 and provides a guideway for an elongate tubular stem 29 to which the brake shoe 30 is attached. This brake shoe is here shown as a disk having a substantially flat lower surface 31 for engagement with the tire of the wheel, the axis of this disk 30 being radial of the wheel with which the brake shoe cooperates.

The stem 29 of the brake shoe is internally screw threaded as shown at 32 (Fig. 7) for the reception of an externally screw threaded plug 33 to which the lower end of a length of piano wire or cable 34 is secured by a swivel connection of any desired type. A lock nut 35 is also arranged within the tubular stem 29 and may be screwed up tight against the lower end of the plug 33 thereby to hold the latter in adjusted position. However by removing the screw 35, a screw driver may be inserted upwardly through the brake shoe and into engagement with a slot 33^a in the lower end of the plug and the plug may be turned thereby to vary the effective length of the wire 34.

Referring to Fig. 8, the lower end 7^a of each front leg of each unit is provided with spaced internal bushings 36 and 37 respectively which are brazed or welded in position and which provide bearings for a long sleeve 38 which is integral or fixedly united to a collar 39 which forms the upper portion of a forked bracket 40 (Fig. 1) which provides bearings 41 for a wheel provided with a resilient tire 42 and preferably of the same diameter as the rear wheel. The forked bracket 40 as shown in Fig. 1, is bent so that the axis 41 of the front wheel does not lie in the vertical

plane of the front leg. The bearing sleeve 38 is free to turn in the bushings 36 and 37 and thus the front wheel freely swivels with reference to the lower end 7^a of the front leg.

The bearing sleeve 38 is shaped to provide a spring housing chamber 43 within which is arranged a long coiled spring 44, the lower end of which bears against a brake shoe 45. This brake shoe has a stem 46 which is arranged to slide in an axial bore in a bushing 47 disposed within the sleeve 38 and which constitutes the inner wall of the spring chamber 43. A stem 46 (similar to the stem 29 of the rear wheel brake) is provided with an internal longitudinally adjustable plug (not shown) to which the lower end of the flexible connector 34^a is secured by any suitable swivel union. The brake shoe 45 is provided with a lower contact surface which is of frusto-conical shape and of such slope that its surface, which at any time engages the tire 42 of the front wheel is in a plane substantially tangent to the tire. By making the brake shoe of the shape just described it is equally effective regardless of the position of the front wheel as the latter swivels about the axis of the lower part 7^a of the front leg.

The flexible transmitters 34 and 34^a (preferably lengths of piano wire or substantially inextensible, non-twisting cable) lead upwardly through the hollow legs of the unit and into the members 8 and 8^a respectively of the hand-supporting rail.

Referring to Figs. 9 to 12, the opposed ends 8^m of the parts 8 and 8^a respectively of the hand-supporting rail are shown as of enlarged diameter, for example as the result of swedging, and within these enlarged portions are welded or brazed internally right and left-hand screw threaded collars 8ⁿ, respectively. The tubular guide sleeve 8^x (Fig. 10) is provided with screw threaded end portions 8^z which engage the collars 8ⁿ respectively. The threads at opposite ends of the guide 8^x are of right and left pitch respectively, so that when engaged with the collars 8ⁿ and rotated, the sleeve 8^x draws the parts 8 and 8^a of the hand-supporting rail toward each other and into firm engagement with the opposite ends of the member 8^x.

The transmitters 34 and 34^a extend into the opposite ends of the tubular guide member 8^x and the end of each transmitter is secured to a swivel member 49 (Fig. 9) which is arranged to turn freely within a cylindrical plug 50 which slides longitudinally within the bore 51 of the member 8^x.

A cam sleeve 52 (Fig. 11) embraces the member 8^x, being free to turn on the latter, the opposite ends of the cam sleeve bearing against the inner ends of the bushings 8ⁿ so that the cam sleeve may not move axially. This cam sleeve is provided with axially spaced, oppositely inclined cam slots 53 and 54 extending through its wall and with an opening 55 approximately mid-way between said slots. Preferably, the sleeve is finished with two cam slots 53 and two cam slots 54 located at diametrically opposite points. The tubular member 8^x (Fig. 10) is furnished with axially elongate slots 54^a and 55^a which underlie the slots 53 and 54 of the cam sleeve, and is likewise provided with a peripherally elongate slot 55^b which underlies the opening 55. A pin 56 is secured to each sliding plug 50. As here shown at the right-hand side of Fig. 9, the opposite ends of pin 56 project outwardly through diametrically opposite slots 54^a and through the corresponding

cam slots 53. The pin 56 (not shown) for the other plug 50 projects out through the slots 55^a of the member 8^x and into the cam slots 54 of the sleeve 52. A pin 57 passes through the diametrically opposite openings 55 in the sleeve 52 and through slots 55^b of the member 8^x. Preferably, as here shown, a cylindrical hand grip 58 is arranged to embrace the enlarged end portions 8ⁿ of the members 8 and 8^a and to turn upon said enlarged portions, and the pin 57 extends outwardly through openings in this hand grip 58 and is headed over at its opposite ends to prevent its withdrawal.

By turning the hand grip, the pin 57 is rocked freely in the elongate slots 55^a of the stationary member 8^x and transmits motion of the rotation to the cam sleeve 52. When the cam sleeve 52 is turned, the pins 56, by engagement with the sloping cam slots 53 and 54, cause the plugs 50 to move toward or from each other. In moving toward each other they draw on the transmitter 34 and 34^a and thus retract the brake shoes from the front and rear wheels. On the other hand, when the plugs 50 are permitted to move away from each other, the springs 27 and 44 urge the brake shoes toward and into contact with the respective wheels. Since the brake-applying springs are of substantial length and open-coiled, they exert a substantially uniform pressure upon the tires of the wheel even though the tires may become worn from use.

In order to prevent application of the brakes, it is preferable to provide locking means to hold the hand grip in the brake-retracting position. For this purpose each handgrip is provided with an elongate slot 8^e near its forward end which receives a sliding latch member 59 whose forward end may be caused to engage a slot in the corresponding bushing 8ⁿ. This latch member 59 may be actuated by the thumb of the user while his hand holds the grip 58. The latch may thus be advanced to lock the hand grip in the brake-retracting position or may be readily retracted to permit the hand grip to turn and thus allow the springs to apply the brakes. The hand grip turns so freely when unlocked that the springs automatically apply the brakes.

As disclosed in the aforementioned patent, each of the stretcher bars 9 is provided with a fixed bracket 61 (Fig. 18) near its forward end, each bracket having a recess 62 which is designed to receive a pin provided at the end of a bar 63 (Fig. 1) extending across the forward edge of a flexible seat member 64. The upper edge of this seat member is secured to the upper rail of the back. When in use, the bar 63 is engaged with the recesses or slots 62 of the brackets, thus holding the seat in operative position as shown in Fig. 1, but when the seat is not to be used the bar 63 is disengaged from the bracket 61 and the flexible seat material may be wound about the bars 2 and 3 of the back. As here illustrated each bracket 61 is provided with a transverse opening 65 (Fig. 1) which is designed to receive a pin 66 (Fig. 18) passing through the forked lower end 67 of a plug 67 which is fixed within the lower end of a tubular crutch socket 69. This crutch socket is preferably of thin rigid tubing and of a length (Fig. 4) such as to reach up substantially to the level of the corresponding hand-supporting rail and is preferably provided at its upper end with a radial flange 70 (Fig. 16). Each hand-supporting rail is provided, at a point just forward of its brake controlling hand grip 58, with a bracket member 71 (Fig. 1) (which may be removable if desired) to which is secured or with which is in-

tegral a horizontal member 72 (Fig. 17) provided with an elongate looped portion 73 (Fig. 16 and Fig. 17) which embraces the upper part of the crutch socket 79 at a point just below the flange 70. The loop 73 is of such length as to permit the upper part of the crutch socket to move laterally within the loop, the crutch socket swinging about its point of connection to the bracket 61. The crutch socket is designed to receive the lower, substantially straight portion 74 of a crutch staff whose upper end portion 75 is preferably curved. At its upper end each crutch socket is designed to receive a plug projecting from an arm-pit rest or pad 76. The straight lower portion of each crutch staff is furnished with a series of spaced openings 77, and the upper part of each crutch socket is furnished with a single opening 78 (Fig. 4). A retaining pin 79 (Fig. 16) may be passed through the opening 78 of the socket and through any selected one of the openings 77 of the crutch staff thereby to hold the crutch staff in vertically adjusted position. Preferably the pins 79 are, as illustrated in Fig. 19, riveted to the closed side of a split resilient ring 80. With this arrangement, when the pin is passed through the openings 77 and 78, the split ring 80 is brought into embracing relation to the socket and thus effectively holds the pin in position until sufficient force is applied to spread the ring 80 and permit the pin to be withdrawn. The arm-pit rest 76 is removably secured to the upper end of the crutch staff by a similar pin and ring 80a. The pin 66 which unites the lower end of the crutch staff socket to the bracket 61 is likewise preferably carried by a split ring 81 (Fig. 18) which embraces the lower end 69 of the socket.

In use, the crutch staffs are disposed as shown in Fig. 4 so that their curved upper parts are concave toward each other. This disposes the arm-pit pads 76 nearer to each other than the hand-supporting rails of the respective units so that the arm-pit pads are conveniently located for the user whose arms extend downwardly in diverging relation and whose hands grip the hand-supporting rails. Since the sockets 69 may swing outwardly or inwardly to a limited extent the position of the pads 76 may vary in accordance with the size of the user and the user is given much more freedom of movement than though the pads were rigidly fixed in position. By removing the pins 79 the crutch staffs may be adjusted vertically to accommodate users of different heights.

While the device is shown in Fig. 4 as provided with crutches, it is obvious that the crutches may be removed either by removing the staffs from their sockets or by removing the sockets from the brackets 61 and 72. If desired the brackets 72 may also be removed from the arm-supporting rails.

In the normal use of the device the two supporting units are disposed so that they are substantially at right angles to the plane of the back, being held in this position by the tooth members 16 and 19 of the hinge means. In this position the operator may stand or sit between the supporting units and may propel himself along in any desired direction, supporting a portion or all of his weight upon the wheels. Since the front wheels readily swivel it is easy to guide the apparatus in any direction. The provision of the brakes makes it possible to provide four wheels for the device without any danger that it will run away and injure the occupant.

When the device is to be stored, or when it is to be transported from place to place (when not

in actual use) the knurled nuts 21 are loosened, the retaining teeth 16 and 19 disengaged and the supporting units swung in opposite directions about the hinge means until the supporting units 5 lie at the opposite sides of the back and in substantially parallel planes. By reason of the inclination of the hinged axes this folding operation raises the front wheels from the ground G as shown in Fig. 3, so that the device may be 10 trundled along upon the rear wheels 24 without danger that the swiveling front wheels 42 will come into contact with the ground and thus impede motion of the device.

Preferably, as hereinabove described, each of 15 the four wheels is provided with a brake, it is contemplated that one pair of brakes might be omitted, if desired. Likewise the seat and crutches may be omitted if it be desired to provide a simpler and less expensive device for 20 more limited use.

While a certain desirable embodiment of the invention has here been shown and described by way of example, it is to be understood that the invention is not necessarily limited to the precise details of construction here shown but is to 25 be regarded as broadly inclusive of any modification or rearrangement falling within the terms of the appended claims.

I claim:

30 1. A portable support for invalid or similar use comprising a pair of supporting units, a back, hinge means uniting the back to each unit, the hinge means being so constructed and arranged that, at will, the supporting units may be folded into substantially parallel relation to the back, and a seat interposed between the supporting units, each unit including a hand-supporting rail and each unit having front and rear wheels, a brake for each wheel of each unit, a spring 40 tending to force each brake into operative engagement with its respective wheel, a sleeve mounted to turn on the hand-supporting rail of each unit, a pair of independent, longitudinally movable plugs within each hand-supporting rail, 45 a flexible transmitter uniting each plug with one of the brakes, respectively, of the corresponding unit, and cam means actuated by rotation of the sleeve for drawing the plugs toward each other thereby concomitantly to release 50 the brakes.

2. A portable support for invalid or similar use comprising a pair of supporting units, a back, hinge means uniting the back to each unit, the hinge means being so constructed and arranged 55 that, at will, the supporting units may be folded into substantially parallel relation to the back, and a seat interposed between the supporting units, each unit including a hand-supporting rail and each unit having front and rear wheels, the front wheels being carried by freely swiveling brackets, a brake for each wheel of each unit, spring means tending to force each brake into operative contact with the respective wheels, a brake controller mounted on each hand-supporting rail, flexible transmitters for transmitting motion from each controller to the brake of the corresponding unit, and individually adjustable means for varying the length of each transmitter.

3. A portable support for invalid or similar use comprising a pair of supporting units, a back, hinge means uniting the back to each unit, the hinge means being so constructed and arranged that, at will, the supporting units may be folded 75 into substantially parallel relation to the back,

and a seat interposed between the supporting units, each unit including a hand-supporting rail and each unit having front and rear wheels, the front wheels being carried by freely swiveling brackets, a brake for each wheel of each unit, spring means tending to force each brake into operative contact with the respective wheels, a brake controller mounted on each hand-supporting rail, the frame of each unit consisting of hollow tubular material, and flexible transmitters extending through the tubular frame from each controller to the brakes of the corresponding unit, and individually actuatable adjusting means for varying the length of each transmitter.

4. A portable support for invalid or similar use comprising a pair of supporting units, a back, hinge means uniting the back to each unit, the hinge means being so constructed and arranged that, at will, the supporting units may be folded into substantially parallel relation to the back, and a seat interposed between the supporting units, each unit including a hand-supporting rail and each unit having front and rear wheels, the front wheels being carried by freely swiveling brackets, a brake for each wheel of each unit, spring means tending to force each brake into operative contact with the respective wheels, a brake controller mounted on each hand-supporting rail, each brake including a shoe and a tubular guide stem, and a flexible transmitter for transmitting motion from each controller to the brakes of the corresponding unit, the tubular stem of each brake having within it a longitudinal adjustable plug to which one end of the corresponding transmitter is attached by a swivel connection.

5. A portable support for invalid or similar use comprising a pair of supporting units, a back, hinge means uniting the back to each unit, the hinge means being so constructed and arranged that, at will, the supporting units may be folded into substantially parallel relation to the back, and a seat interposed between the supporting units, each unit including a hand-supporting rail and each unit having front and rear wheels, the front wheels being carried by freely swiveling brackets, a brake for each wheel of each unit, spring means tending to force each brake into operative contact with the respective wheels, a brake controller mounted on each hand-supporting rail, each brake including a sleeve and a tubular guide stem, and a flexible transmitter for transmitting motion from each controller to the brakes of the corresponding unit, the tubular stem of each brake being internally screw-threaded and having within it a longitudinal adjustable screw-threaded plug to which one end of the corresponding transmitter is attached by a swivel connection.

6. A portable support for invalid or similar use comprising a pair of supporting units, a back, hinge means uniting the back to each unit, the hinge means being so constructed and arranged that, at will, the supporting units may be folded into substantially parallel relation to the back, and a seat interposed between the supporting units, each unit including a hand-supporting rail and each unit having front and rear wheels, the front wheels being carried by freely swiveling brackets, a brake for each wheel of each unit, a brake controller mounted on each hand-supporting rail, each brake including a sleeve and a tubular guide stem, a flexible transmitter for transmitting motion from each controller to the brakes of the corresponding unit, one end of each

transmitter being connected by swivel means to the guide stem of one of the brake shoes, and a coil spring embracing the stem of each brake and arranged to urge the brake shoe toward the periphery of the corresponding wheel.

7. A portable support for invalid or similar use comprising a pair of supporting units and a back and hinge means uniting the back to each supporting unit, the hinge means being so constructed and arranged that, at will, the supporting units may be folded into substantially parallel relation to the back, and a seat normally interposed between the supporting units, each unit including lengths of hollow tubular material shaped to provide a substantially horizontal hand-supporting rail and front and rear legs, a wheel mounted on each leg, the front wheels being mounted in forked bearings which swivel freely with respect to the front legs, a brake for each wheel of each unit, each brake being movable axially of the corresponding leg of its unit, and a spring urging the brake toward the periphery of its respective wheel, and means for retracting each brake from its wheel, said retracting means comprising a tubular hand grip mounted on and coaxial with each hand-supporting rail, a pair of spaced axially slideable plugs within the hand-supporting rail, a cylindrical sleeve nested within the hand grip and free to turn on the hand rail, said sleeve having a pair of axially spaced oppositely sloped cam slots in its walls, means connecting the sleeve and hand grip whereby rotation of the latter turns the sleeve, a projection on each plug which enters one of the respective cam slots whereby rotation of the hand grip causes separation or approach of the plugs, and a flexible transmitter connecting each plug to one of the respective brakes.

8. A portable support for invalid or similar use comprising a pair of supporting units and a back and hinge means uniting the back to each supporting unit, the hinge means being so constructed and arranged that, at will, the supporting units may be folded into substantially parallel relation to the back, and a seat normally interposed between the supporting units, each unit including lengths of hollow tubular material shaped to provide a substantially horizontal hand-supporting rail and front and rear legs, each hand-supporting rail including a tubular guide member provided with a bore constituting a guideway, a pair of plugs sliding in said guideway, a flexible transmitter attached to each plug and extending through the hollow hand-supporting rail and to the lower end of one of the respective legs, a wheel carried by each leg, a brake for each wheel, each brake being movable axially of the leg and a spring urging each brake toward the periphery of its respective wheel, means connecting the lower end of each transmitter to one of the respective brakes, a cylindrical sleeve mounted to turn on each of said tubular guide members, each sleeve having a pair of axially spaced, oppositely inclined cam slots in its wall, a pin projecting from each plug into one of said cam slots, and means for turning the sleeve, thereby to cause the plugs to move toward or away from each other and thus release or apply the brakes to the several wheels.

9. A portable support for invalid or similar use comprising a pair of supporting units and a back and hinge means uniting the back to each supporting unit, the hinge means being so constructed and arranged that, at will, the support-

ing units may be folded into substantially parallel relation to the back, and a seat normally interposed between the supporting units, each unit including lengths of hollow tubular material shaped to provide a substantially horizontal hand-supporting rail and front and rear legs, each hand-supporting rail including a tubular guide member provided with a bore constituting a guideway, a pair of plugs sliding in said guideway, a flexible transmitter attached to each plug and extending through the hollow hand-supporting rail and to the lower end of one of the respective legs, a wheel carried by each leg, a brake for each wheel, each brake being movable axially of the leg and a spring urging each brake toward the periphery of its respective wheel, means connecting the lower end of each transmitter to one of the respective brakes, a cylindrical sleeve mounted to turn on each of said tubular guide members, each sleeve having a pair of axially spaced, oppositely inclined cam slots in its wall, a pin projecting from each plug into one of said cam slots, and means for turning the sleeve, thereby to cause the plugs to move toward or away from each other and thus release or apply the brakes to the several wheels, and a manually-actuable locking element operative

at will to connect the cylindrical sleeve to a relatively stationary portion of the hand-supporting rail.

BUTLER AMES.
